(57) **CLAIM**

The ornamental design for a display screen with graphical user interface as shown and described.

DESCRIPTION

FIG. 1 is a front view of a display screen with graphical user interface;

FIG. 2 is a detail view of the portion identified as "2" in FIG. 1;

FIG. 3 is a detail view of the portion identified as "3" in FIG. 1;

FIG. 4 is a detail view of the portion identified as "4" in FIG. 1; and,

FIG. 5 is a detail view of the portion identified as "5" in FIG. 1.

In the drawings, the dot-dash broken lines indicate where enlargements have been taken only and form no part of the claim, and the outermost broken lines showing a display screen illustrate portions of the article and form no part of the claimed design.

1 Claim, 5 Drawing Sheets
